SUSPENDER SUIT CONSTRUCTION

Samuel Rossby, New York, N. Y.

Application July 18, 1942, Serial No. 451,386

4 Claims. (Cl. 2—80)

This invention relates to new and useful improvements in a suspender suit for children, or in other similar garments.

More particularly, the invention relates to a garment having a waist portion and a fundament covering portion which may be a pair of panties, a pair of pants, a skirt, or similar portion, depending upon the type and character of the garment. The invention particularly proposes the provision of a pair of forwardly and rearwardly spaced openings on each of the shoulders of the waist portion through which shoulder straps of the garment are laced and which prevent the shoulder straps from slipping off the shoulders.

Still further the invention contemplates a certain construction for said pair of forwardly and rearwardly spaced openings.

Furthermore, a modification is proposed in which each shoulder is provided with auxiliary openings through which the shoulder straps may be laced for supporting the shoulder straps from slipping off the shoulders, but supporting them in different positions on the shoulders, as selected.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a suspender suit for children constructed in accordance with this invention.

Fig. 2 is a plan view of Fig. 1.

Fig. 3 is a rear elevational view of Fig. 1.

Fig. 4 is a fragmentary vertical sectional view taken on the line 4—4 of Fig. 1.

Fig. 5 is a plan view of a suspender suit for children constructed in accordance with another form of this invention.

Fig. 6 is a fragmentary enlarged vertical sectional view taken on the line 6—6 of Fig. 5.

The suspender suit for children, and other garments, in accordance with the form of the invention illustrated in Figs. 1—4 inclusive, includes a combination garment comprising a waist portion 10 and a fundament covering portion 11. The waist portion 10 may be in the form of a shirt, a waist, a jacket or other similar portion of a garment. The fundament covering portion 11 may comprise panties, pants, a skirt, or other similar portions.

Shoulder straps 12 are connected with the fundament covering portion 11 and engage across

the shoulders of the waist portion 10. Each shoulder of the said waist portion 10 is provided with a pair of forwardly and rearwardly spaced openings 13 and 14 through which its shoulder strap 12 is laced.

The shoulder straps 12 are permanently attached at their rear ends by stitches 15 or other holding elements to the back of the fundament covering portion 11. At the back the shoulder straps 12 are crossed, as clearly illustrated in Fig. 3. They then pass through the pairs of openings 13 and 14 and continue downwards along the front of the waist portion 10 and are releasably connected by releasable fastening elements 16 with the top of the front portion of the fundament covering portion 11. The openings 13 and 14 may be in the nature of button holes constructed on a conventional buttonhole making machine. An important feature of the invention resides in the fact that the shoulder straps 12 are held from slipping off the shoulders of a wearer.

In Figs. 5 and 6 a modified form of the invention has been disclosed which is very similar to the prior form, distinguishing merely in the fact that each shoulder portion is provided with a laterally spaced pair of forwardly and rearwardly spaced auxiliary openings 13' and 14' through which the shoulder straps 12 thereof may be laced when desired. A flap 18 is mounted on the under face of each shoulder and normally extends across the latter mentioned auxiliary openings 13' and 14' and is adapted to be folded across the first mentioned openings 13 and 14. Fastening means such as snap fasteners 19 are mounted upon portions of the inner face of each shoulder and on the flaps 18 for holding the flaps in either of their positions.

In other respects this form of the invention is identical to the previous form and like parts are identified by like reference numerals.

Normally, the flaps 18 extend across and cover the auxiliary openings 13' and 14'. When it is desired to shift the positions of the shoulder straps 12 they may be unthreaded from the openings 13 and 14 and threaded or laced through the openings 13' and 14'. Then the flaps 18 are folded across to extend beneath the openings 13 and 14. The garment is then used in this condition.

It is to be understood that the size, material and style of the garment may be changed as desired, and the shoulder straps 12 may also be held in position by suitable short loops, on the shoulders of the waist portion of the garment.

While I have illustrated and described the pre-

ferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In combination with a garment having a waist portion and a fundament covering portion, shoulder straps connected with said fundament covering portion and engaging across the shoulders of said waist portion, and each shoulder of said waist portion having a pair of forwardly and rearwardly spaced openings through which the shoulder strap thereof is laced. 10
2. In combination with a garment having a waist portion and a fundament covering portion, shoulder straps connected with said fundament covering portion and engaging across the shoulders of said waist portion, each shoulder of said waist portion having a pair of forwardly and rearwardly spaced openings through which the shoulder strap thereof is laced, and also having a laterally spaced pair of forwardly and rearwardly spaced auxiliary openings through which the shoulder strap thereof may be laced. 20
3. In combination with a garment having a waist portion and a fundament covering portion, shoulder straps connected with said fundament 25

covering portion and engaging across the shoulders of said waist portion, each shoulder of said waist portion having a pair of forwardly and rearwardly spaced openings through which the shoulder strap thereof is laced, and also having a laterally spaced pair of forwardly and rearwardly spaced auxiliary openings through which the shoulder strap thereof may be laced, and a flap mounted on the inner face of each shoulder and normally extending across the latter mentioned auxiliary openings and adapted to be folded across the first mentioned openings.

4. In combination with a garment having a waist portion and a fundament covering portion, shoulder straps connected with said fundament covering portion and engaging across the shoulders of said waist portion, each shoulder of said waist portion having a pair of forwardly and rearwardly spaced openings through which the shoulder strap thereof is laced, and also having a laterally spaced pair of forwardly and rearwardly spaced auxiliary openings through which the shoulder strap thereof may be laced, a flap mounted on the inner face of each shoulder and normally extending across the latter mentioned auxiliary openings and adapted to be folded across the first mentioned openings, and fastening means for holding said flaps in either of their positions.

SAMUEL ROSSBY.
